UNITED STATES PATENT OFFICE.

ARTHUR W. BURWELL AND LAYTON O. SHERMAN, OF CLEVELAND, OHIO;
SAID BURWELL ASSIGNOR TO SAID SHERMAN.

PROCESS OF DESULFURIZING CRUDE PETROLEUM.

SPECIFICATION forming part of Letters Patent No. 738,656, dated September 8, 1903.

Application filed February 27, 1903. Serial No. 145,319. (No specimens.)

To all whom it may concern:

Be it known that we, ARTHUR W. BURWELL and LAYTON O. SHERMAN, citizens of the United States, residing at Cleveland, in the county of Cuyahoga and State of Ohio, have invented certain new and useful Improvements in Processes of Desulfurizing Crude Petroleum, of which the following is a specification.

10 This process is especially intended for the treatment of petroleum containing a large amount of sulfur, such as Lima oil.

In carrying out the process the crude oil is distilled and the vapors are carried over 15 finely-divided iron oxid and quicklime, preferably in admixture. It is important to the success of the process that both the vapors of oil and the mixture of iron oxid and lime should be entirely free from water, either 20 combined or physically held. The partially-desulfurized vapors are then condensed and the distillate is subjected to the usual treatment with sulfuric acid and caustic alkali, whereby the percentage of sulfur in the oil is 25 reduced to a minimum.

The process may be carried out by the use 30 of widely-different forms of apparatus. One which has been found suitable for the purpose is shown in the accompanying drawing, 35 in which the figure is a vertical longitudinal section through the heating-furnace, still, and chamber containing the iron oxid and lime.

The still 1 may be of any usual construction, that shown being a horizontal cylinder 35 of boiler-iron set in a furnace having a fire-grate 2, fuel and ash-pit doors 3 4, and stack 5. An outlet 6 for the vapors leads from the top of the still near its rear end. From the 40 side of this outlet leads a branch pipe 7. Upon the rear portion of the still is supported a chamber 8, containing a series of horizontal foraminous shelves 9, of perforated iron or heavy wire-cloth. The shelves are 45 arranged as baffles, alternate shelves extending from opposite ends of the chamber, so that the vapors rising from the still pass back and forth between the shelves, as well as through the shelves, before they escape from the 50 chamber through the outlet 10 in its upper

wall. In employing this apparatus to carry out the process the shelves 9 are charged with a finely-ground and carefully-dried anhydrous iron oxid, preferably iron ore on account of its cheapness, and freshly-burned 55 lime entirely free from water. The ground iron ore and quicklime are preferably mixed and a thin layer of the mixture placed on each of the shelves. The iron oxid and lime may, however, be placed on alternate shelves, 60 the lime being placed on the lowermost shelf. The crude oil in the still is now heated until vapors begin to escape through outlet 6. As it is important that the vapors which pass through chamber 8 to be treated by the material therein shall be entirely free from water, a valve in pipe 7 (not shown) is opened and the slide-valve 11, which covers outlet 6, is closed, so that the first portions of the oil-vapors which contain water escape through 70 pipe 7. As soon as the water in the charge of oil has been entirely distilled off the valve in pipe 7 is closed and the slide-valve 11 is opened, so that the water-free vapors pass through the chamber 8 and over and through 75 the shelves and the treating materials carried upon them. The temperature of the materials in chamber 8 is merely high enough to prevent condensation of the oil-vapors, and this temperature is readily maintained 80 without special heating means by the heat of the vapors themselves and by the proximity of the chamber to the still. The iron oxid and quicklime directly remove a considerable portion of the sulfur in the oil, 85 but in general not enough to render it commercially available. The vapors from outlet 10 are condensed and the distillate is subjected to the usual treatment with sulfuric acid and caustic alkali. This second treatment practically removes all of the sulfur from the oil or reduces it to the desired minimum. The reagents in chamber 8 seem to break up the sulfur compounds in the oil and to not only remove a portion of the sulfur, 95 but to bring the remaining portion into a condition where it is readily removed by the usual acid-and-alkali treatment.

Calcined dolomite entirely free from water or other alkaline-earth oxid may be substi- 100

tuted for quicklime, and any anhydrous iron oxid may be employed, although the sesqui-
oxid is most available.

We are aware that others have proposed
5 already to desulfurize oil-vapors by bringing
them in contact with either iron oxid or lime.
Our invention contemplates the use of both
water-free iron oxid and quicklime, the joint
action of the two reagents being required.

10 We claim—

1. The process of desulfurizing crude pe-
troleum, which consists in distilling the pe-
troleum, and passing the oil-vapors in contact
with oxids of iron and an alkaline-earth metal,
15 both of said oxids being entirely free from
water, as set forth.

2. The process of desulfurizing crude pe-
troleum, which consists in distilling the pe-
troleum, and passing the oil-vapors in contact
20 with a mixture of finely-divided oxids of iron
and an alkaline-earth metal, both of said ox-
ids being entirely free from water, as set
forth.

3. The process of desulfurizing crude pe-
troleum, which consists in distilling the pe-
troleum, rejecting the first portions of the va-
por containing water, and passing the other
oil-vapors in contact with water-free oxids of
25 iron and an alkaline-earth metal, as set forth.

4. The process of desulfurizing crude pe-
troleum, which consists in distilling the pe-
troleum, rejecting the first portions of the the
vapor containing water, and passing the other
oil-vapors in contact with a mixture of finely-
30 divided, water-free oxids of iron and an alka-
line-earth metal, as set forth.

5. The process of desulfurizing crude pe-
troleum, which consists in distilling the pe-
troleum, passing the oil-vapors in contact
40 with oxids of iron and an alkaline-earth metal,
both of said oxids being entirely free from
water, condensing the treated vapors, and
subjecting the distillate to the usual treat-
ment with acid and alkali, as set forth.

45 6. The process of desulfurizing crude pe-
troleum, which consists in distilling the pe-
troleum, passing the oil-vapors in contact
with a mixture of finely-divided oxids of iron

and an alkaline-earth metal, both of said oxids
being entirely free from water, condensing 50
the treated vapors, and subjecting the distil-
late to the usual treatment with acid and al-
kali, as set forth.

7. The process of desulfurizing crude pe-
troleum, which consists in distilling the pe- 55
troleum, rejecting the first portions of the
vapor containing water, passing the other oil-
vapors in contact with water-free oxids of
iron and an alkaline-earth metal, condensing
the treated vapors, and subjecting the distil- 60
late to the usual treatment with acid and al-
kali, as set forth.

8. The process of desulfurizing crude pe-
troleum, which consists in distilling the pe- 65
troleum, rejecting the first portions of the
vapor containing water, passing the other oil-
vapors in contact with a mixture of finely-
divided, water-free oxids of iron and an al-
kaline-earth metal, condensing the treated
70 vapors, and subjecting the distillate to the
usual treatment with acid and alkali, as set
forth.

9. The process of desulfurizing crude pe-
troleum, which consists in distilling the pe- 75
troleum, and passing the oil-vapors in contact
with oxids of iron and an alkaline-earth metal,
both of said oxids being entirely free from
water, maintained at a low temperature,
merely sufficient to prevent condensation of
80 the vapors, as set forth.

10. The process of desulfurizing crude pe-
troleum, which consists in distilling the pe- 85
troleum, and passing the oil-vapors in contact
with a mixture of finely-divided oxids of iron
and an alkaline-earth metal, both of said oxids
being entirely free from water, maintained
at a low temperature, merely sufficient to pre-
vent condensation of the vapors, as set forth.

In testimony whereof we affix our signa-
tures in presence of two witnesses.
